TO SOCIÉTÉ RENARD FRÈRE ET FILS, OF NONANCOURT, FRANCE.

POWER LOOM FOR CARPETS.

Application filed January 5, 1923, Serial No. 610,851, and in France April 26, 1922.

When we examine an oriental carpet, preferably one of fine ground texture, we are struck by the close fitting of the wefts. We see that with the usual mechanical method 5 of weaving, it will be practically impossible to obtain the same number of wefts to the inch.

This results from the fact that hand weavers have always understood the necessity for entering a loose weft into the shed, beating this weft up with a mallet and using thus two or three times as many wefts as it would be possible to employ in the usual power loom.

15 When this loose weft is closely applied to the fabric it does not contract the fabric but follows the contours of the warp threads without jamming them and the weft is placed in position more easily as the friction 20 with the warp threads is insignificant.

The object of the present invention is to provide means for mechanically inserting a loose weft into the fabric produced by power looms, more especially in those for 25 making Smyrnan, Persian, wound or other knotted carpets.

This loose weft is obtained by the insertion by the shuttle of an ordinary straight weft in the usual known manner, this 30 straight weft being subsequently modified by suitable means into an undulated line, which consequently increases the length of the usual weft. This increase of length is regulated and controlled at will according 35 to the quality of the fabrics.

For this purpose, the applicants have devised means for undulating the weft after its insertion in the shed in the usual manner by the shuttle, the loom stopping after the passage 40 of the shuttle so as to allow the undulating process to be effected. This undulated weft applied to the fell by the reed surrounds the warp threads without tension and fills up all the interstices, the action 45 length of the thread required for the undulation (see Figs. 1^a and 2) being drawn supplementarily from the shuttle when the latter is at rest.

The invention will be readily understood 50 by reference to the accompanying drawings illustrating two embodiments of the inventive idea and wherein

Fig. 1 illustrates diagrammatically a section of a warp.

Fig. 1^a is a diagrammatic top plan view illustrating an undulating weft. 55

Fig. 2 is a diagrammatic end view of the undulating weft.

Fig. 3 is a side elevation illustrating one type of reed that may be employed. 60

Fig. 4 is a side elevation of one type of undulator or rocking member.

Fig. 5 is a detail sectional view on the line A—B of Fig. 4 illustrating the beveled portion of the undulator shown in Fig. 4. 65

Fig. 6 is a side elevation partly in section of the assembled mechanism.

Fig. 7 is a side elevation and Fig. 8 a top plan view, on a reduced scale, of a sliding carriage that may be employed, Figs. 7^a 70 and 8^a are respectively a front elevation and a plan of the sliding carriage mounted on the batten.

Fig. 9 is a side elevation, partly in section, illustrating a second embodiment of 75 the present invention.

Fig. 10 is a side elevation of the mechanism illustrated in Fig. 9.

Fig. 11 is a detail side elevation illustrating the mounting of the undulators. 80

Fig. 12 is a detail side elevation illustrating one type of mounting that may be employed for the separators and

Fig. 13 is a detail view partly in section, illustrating one of the separators. 85

Referring to the drawings, wherein like reference numerals refer to like parts throughout the several views, Fig. 1 illustrates a section of a warp; $x \dots x'$ show the warp threads in section; the weft $y \dots y'$ 90 thrown by the shuttle in the usual manner is straight. Fig. 2 is a similar diagrammatic view in which the weft is undulated, this figure representing the crossing of the warps; x has been brought below, x' above. From 95 this figure it is seen that if a weft $z \dots z'$ longer than usual, has been thrown and if this excess of length has been distributed regularly and proportionately over the width of the fabric, and if the reed has, 100 when the shed has been closed, drawn up this weft against the preceding weft, thread $y \dots y'$, the excess of the weft will be absorbed after crossing the warps, as shown in Fig. 2, the undulated weft separating 105 the warps and placing them at a distance apart equal to its diameter.

We have then in Fig. 1 a fabric with an

ordinary straight weft and in Fig. 2 a fabric with an undulated weft.

In order to mechanically obtain this undulated weft, an ordinary weft $z \dots z'$ is thrown and the shed closes lightly so as to allow the weft to slide easily between the two warp banks. In other words, the warp rubs lightly on the weft so as to allow it to preserve the form which has been given to it. 10 Then the loom, properly so-called, stops. By means of rocking members conveniently placed under and moving parallel to the warp, the weft inserted in the warp has the form of a horizontal sinuous line (Fig. 1^a, 15 which is a plan view of the warp and weft threads), the surplus thread necessary for this operation being furnished by the shuttle at rest.

When the undulation is effected and the 20 rocking members are returned to their normal position below the warp, the reed beats up the undulated weft against the fell and the weft by its extra length surrounds the warp threads without tension, as shown in 25 Fig. 2.

The batten of the weaving loom is moved in the usual known manner, but a special mechanism stops the loom every time that a weft is to be undulated.

30 As shown in Fig. 3, the reed is composed of stamped steel sheets reinforced at 3 by small riveted plates in order to impart the required thickness and provide the required distance between the adjacent dents. Preferably a notch 5 is provided in one edge of the reed for engaging a projection of the frame work as is illustrated in Fig. 6. Such an arrangement insures parallelism of all the dents of the reed and facilitates the 40 mounting of the latter.

The reed is provided with an opening 1, which is preferably formed when the latter is stamped out, through which opening passes a rod for supporting the rocking 45 member to be described hereinafter. 9 is a projection on the reed which permits the weft to take up its increase of length, as explained later.

Fig. 4 shows the undulator or rocking 50 member. 1 is the axis of oscillation. Each rocking member or undulator is pivoted on a dent of the reed. 6 and 7 are members with beveled but not cutting edges. 13 is a projection which is engaged by a lever to rotate 55 the undulator around its axis, thereby bringing the undulator to position below the warp; 8 is a part forming a quadrant of a circle.

Fig. 5 shows in section the beveled parts 60 6 and 7 which force the weft against the projections 9 of the dents of the reed.

Fig. 6 is a general view of the arrangement mounted on the foot of the frame; $x \dots x, x' \dots x'$ are the warp threads.

65 The rocking member of Fig. 4 is shown

mounted; it oscillates about its axis 1. The interrupted lines show it in its closed or working position, the full lines in the normal position. In this latter position, it lies below the warp threads and allows the free 70 passage of the shuttles.

A weft Z is thrown in the usual manner between the warp threads $x \dots x, x' \dots x$. These latter not being completely closed, the weft can consequently be pushed by the 75 rocking member without great force against the projection 9 of the reed, is forced between two adjacent dents of the reed and consequently lengthened, the quantity of thread necessary for the excess of length 80 being drawn from the shuttle.

It should be remarked that the different rocking members placed over the whole width of the loom do not all work at the same time but in succession, commencing on 85 the opposite side from the shuttle, in order to allow the thread to be drawn from the shuttle as the action is progressively passed on. Also, each undulating device rests in its working position during some time in 90 order to maintain the undulated weft in the reed and to prevent the adjacent undulator from deranging it when working.

The weft is thus undulated between the 95 dents of the reed and is ready to be placed in the fabric without any effort of the batten or reed, and this condition is important for efficient working.

This undulated weft, not drawing either 100 on the warp threads or on the selvage, does not contract the latter, but on the contrary it fills it up, maintains the warps at their exact position and consequently obviates the necessity for the use of temples.

The arrangements for operating the rock- 105 ing member will now be described.

In Fig. 6 the batten 22 is shown in section and hatched. The reed is placed on this batten in the manner described previously. 14 and 15 are two rails extending 110 along the whole length of the batten below the rounded part 8 of the rocking members. The rails are secured upon pieces 14^a and 15^a conveniently secured to the batten 22. The rails are arranged so as to provide below the necessary space for a sliding carriage (Figs. 7 and 8) which may be moved by a cam, lever, chain or rope from one end to the other of the frame, by a movement similar to that of the rods of velvet pile 120 looms.

The sliding carriage has an eye 18 on 115 which a member 19 provided with an inclined portion at one end thereof, oscillates. The thickness of this member corresponds to the distance apart of the rails 14, 15 so that it passes freely between the latter.

On each side of this member at 20 are 125 two projecting rollers adapted to rest on the rails 14, 15. The height of these rollers 130

is variable and controlled by an adjustable member 21 resting on a plant surface 16.

The rails 14, 15 are provided at each end with an arrangement which permits the 5 rollers 20 to be placed either above or below the rails, consequently allowing the inclined portion of the undulator 19 to act on the rocking members or to be removed from the latter.

10 The operation is as follows: At the right end of the frame, the rails 14 and 15 end in two tongues 52 of the same thickness forming extensions of the rails (Figs. 7^a and 8^a). These tongues oscillate about a common axle 53 and a spring 54 tends to maintain the tongues 52 in their closed position, that is to say downwards.

An aperture 55 is provided near the right hand end of the rails 14, 15, as viewed in 20 Fig. 8^a, in order to permit rollers 20 and the mechanism employed for producing the undulation to pass below said rails. Obviously, aperitüre 55 may be provided at the opposite end, if desired. If points 52 are 25 placed on the left hand end of rails 14, 15, as illustrated in Figs. 7^a and 8^a, aperitüre 55 will of course be formed adjacent the right hand end of rails 14, 15. If, when so arranged, the sliding carriage is placed 30 below the rails and adjacent the right hand end thereof and is drawn to the left, the rollers 20 will engage the members 52 to raise and pass beneath the same, whereupon springs 54 again force members 52 downwardly into engagement with the plate 16. When the carriage is drawn to the right the 35 rollers 20 remount the tongues 52 and progressively arrive above the rails 14, 15 on which they slide, drawing the inclined portion of the undulator 19 above the rails, under the projection 8 of the rocking members and thereby causing the latter to oscillate.

It should be remarked that it is the 40 inclined portion 56 of the undulator which causes the rapid rise of the rocking members, effecting thereby the undulation by thrusting the weft between two dents of the reed, whilst the left hand end of the undulator 19 serves to maintain the rocking members which have just operated in their closed position, retaining thus for a certain time the undulated weft between the dents of the reed.

55 At the end of their path, the rollers 20 being no longer supported by the rails 14, 15 fall into the aperitüre 55 drawing with them the undulator below the rails and permitting the return to the left of the carriage without acting on the rocking members.

As soon as the undulator 19 is moved past the rocking members, the latter should fall by their own weight into their normal position, indicated in full lines in Fig. 6; however, in order to ensure this action a

rod 22 controlled by a cam, coming into operation at the end of the undulating process, rises and consequently pushes the projection 13 of any rocking member which for some reason or another has not fallen and 70 remained in its raised position, preventing consequently any rocking member from being raised by shaking or for any other reason.

A second embodiment of the present invention is illustrated in Figs. 9 to 13 inclusive. The method of operation of this embodiment consists in causing two rocking members to cross one another and operate on the weft to undulate the same. Referring to Fig. 4, 22 is a part of the batten which is preferably made of cast iron. This member supports a reed 23 of the usual form held in position by a plane cast-iron or steel member 24, tightened by a set 80 screw 25.

In front of this part and integral with the support of the frame, is a plane portion 27, 28 on which is screw-threaded or riveted a member 26 of U form which extends over all the width of the frame and which is accurately plane. On this member and at regular intervals apart are small cast-iron supports 29 which are connected to the plates 24 by rods 30 fixed by screws or bolts 31, 32 and which form the race for the shuttle thrown across the loom in the usual manner.

On the opposite side of the member 26 are similarly small cast-iron supports 33, mounted on a member 34 which serves as a supporting axis for a cylindrical member 35 provided with a rod formed as a tapered blade or undulator 36, performing the same function as the rocking member represented in Fig. 4.

Each member 36 pivoting about its axle 34 engages the weft thread Z (Fig. 9) adjacent its upper end and displaces said thread horizontally. For this purpose it pivots about its axis in the direction of the arrow f, but it always tends to return to its lower position shown in full lines in Fig. 9 under the influence of a spring 37 fixed at 38 and 39.

These undulators or weft beater arms 36 extend across the loom and each of them receives its movement individually.

Opposite these undulators 36 is a series of separators disposed end to end, extending across the width of the loom parallel to the undulators. Each system of separators is composed of a cylinder 40 oscillating about an axle 42; on the cylinder 40 are fixed tapered rods, as shown in Fig. 12 similar to the rods of the undulator. The axle 42 is constituted by an extension of the cylinder 40 forming a part which is common to two adjacent separators. For this purpose each cylinder has at the end opposite to the junction, a hole in which an extension 42 of an adjacent cylinder enters. This axle also ex-

tends through an opening 41 in the frame supports 29 and thus sustains the whole system together, so that between two adjacent frame supports 29 there is a separator system oscillating about its axle 42.

It is obvious that the separator system could be constituted by a single separator extending across the whole of the loom, but the present arrangement allows the separators to act more easily with less friction and better parallelism, it also permits the employment of axles and members of reduced dimensions, which is useful on a loom where the dimensions are restricted, so that between each frame support 29 there is a separator oscillating about its axle 42.

The blades of the separator 40 may be represented by even numerals and the blades 36 by odd numerals, or conversely. A spring tends to maintain the separators so that the blades 43 rest in their lower position as shown in full lines in Fig. 9.

On the cylinders 35 and 40 of the undulators and separators are screw-threaded pivots 48, 47 serving as axles for little steel rollers 46, 45.

Preferably an endless chain 49 extends along the member 26 throughout the entire width of the loom. The thickness of this chain is calculated so that it cannot act on the rollers 45, 46, but at convenient places small steel plates 50, 51 of suitable form and height are fixed on each side of this chain to raise the rollers 45 of the separators, and 35 46 of the separate undulators. The plate 50 acting on the separators is preferably rectangular, Fig. 10, in order to maintain the blades 43 of the system constantly raised, while the plate 51 of the undulators 36 is 40 an inclined plane (Fig. 10), allowing the blades to be raised progressively one after the other and maintaining them raised for the time necessary for the undulation. In Fig. 10, the first plate of the cam 50, which 45 would hide the first plate of the cam 51, has been omitted.

This undulation operates as follows:— Suppose the warp threads in their closed position, a weft thread Z having been 50 thrown across the shed but the reed not to have beaten up the thread. Directly after the weft has been thrown, the frame being stopped for the duration of the undulation the chain 49 effecting the winding is set in 55 movement.

The plate 50 engaging the roller 45 of the first separator, raises it, and the length of this plate 50 on the driving chain is calculated in order to maintain the bar in this 60 position as long as may be required.

The blades 43 of the separators being thus maintained in the raised position, the plate 51 of the driving chain raises the first blade 36 by abutting against the roller 46. This 65 blade 36 crosses between the first and second

blade 43 of the separator, drawing the weft with it horizontally across these blades, the required increase of length of the weft being drawn from the shuttle. It maintains it in this position for a time sufficient for 70 four or five separate blades to perform the same actions.

When the last blade of each separator is reached by the particular undulator, the plates 50 and 51 arrive at the end of their 75 path and cease to act, separators and individual blades falling into their normal position under the action of the springs 37 and 44, leaving the weft thread as an interrupted line in the warp. To ensure certainty of action and to avoid any disarrangement while this weft thread is being drawn in the interrupted line, the plates 50 and 51 continue to act an appreciable interval after 80 the work is finished, and the separators and the undulators only fall when the second separator has connected its work.

It should be noticed that the separators are raised successively one after the other, and as explained above the weft lies in the 90 warp threads not as a straight line but as a line regularly undulated.

Separators and undulators having been lowered the frame is set in motion, the reed beats up the undulated weft in the usual 95 manner. This weft does not wedge the warp threads, but lies against them as shown in Fig. 1a. In this manner the insertion of a weft thread much longer than the length of the reed is obtained. This length is variable 100 according to the heights of the plates 50, 51 of the driving chain and is controlled in consequence.

While only two embodiments of the invention have been illustrated and described in 105 the accompanying drawings it will be understood that the invention is capable of a variety of mechanical expressions. It is to be expressly understood that the drawings are for purposes of illustration only and are 110 not designed as a definition of the limits of the invention, reference being had for this purpose to the appended claims.

What we claim is:

1. In a loom, the combination of a shuttle, 115 a plurality of axles parallel to the weft thread, a plurality of blades pivoted about said axles, means for successively rotating said blades after the passing of the shuttle in the direction that pushes the weft thread away from the fabric, rigid blades for stopping the weft thread, and a reed to apply the weft thread against the fabric.

2. In a power loom, a shuttle, a plurality 125 of separators having rigid blades, a series of individually actuated undulators, means for actuating said separators whereby they serve to support the weft in the position given it by the shuttle, means for successively moving said undulators between said rigid 130

blades in order to push the weft between the blades, and means for moving said undulators and separators below the weft.

3. In a power loom, a shuttle, rocking members provided with rigid blades and each having an axle extending into a recess in the next adjacent member for centering said members and preserving their individual freedom of movement, a series of individual
- 5 undulators, means for controlling said members whereby they serve as a support for the weft in the position given by the shuttle, means for successively moving the undulators between said rigid blades in
- 10 order to push the weft between the blades, and means for moving said undulators and separators below the weft.
- 15 4. In a power loom, rocking members pro-

vided with rigid blades and having interfitting axles for centering the members and preserving their individual freedom of movement, a series of individually actuated undulators, means for successively moving said undulators between said blades whereby the weft is forced between said blades, an 20 endless chain extending across the width of the loom, a plurality of plates constituting 25 cams secured to said chain, arms for each of said members and separators adapted to be engaged by said plates whereby said members and separators are actuated to undulate the weft.

In testimony whereof we have signed this specification.

PIERRE RENARD.
FERDINAND RENARD.
